UNITED STATES PATENT OFFICE

2,611,273

AUTOMATIC LOW WATER GAS SHUTOFF

Ray C. Posseley, Mendota, Ill.

Application April 6, 1945, Serial No. 586,960

1 Claim. (Cl. 74-2)

1. This invention relates to an automatic low water gas shut-off, which is especially adapted to completely cut off the flow of gas in a gas line, or the like, when pressure upon the control diaphragm falls below a predetermined degree.

A further object of this invention is the production of a simple and efficient means for automatically disconnecting the control link for the shut-off valve in a manner whereby the weight of the actuating link and the falling of the link away from the diaphragm-actuating mechanism will cause the valve to completely close.

Other objects and advantages of the present invention will appear throughout the following specification and claim.

In the drawing:

Figure 1 is a side elevational view of the automatic shut-off;

Figure 2 is a front elevational view, the actuating link being broken away;

Figure 3 is a top plan view of the cut-off valve; and

Figure 4 is a plan view of the abutment pin.

By referring to the drawing, it will be seen that 10 designates the casing of the actuating mechanism which carries a diaphragm 11. The casing 10 is provided with a threaded inlet neck 12 which is adapted to be connected to a line supplying pressure such as steam, or the like, to the diaphragm 11. An abutment pin 13 is secured to the diaphragm 11 by means of a nut 14 which is threaded upon the inner end of the pin 13 and engages the rear face of the diaphragm 11. An abutment flange 15 engages the front face of the diaphragm 11 to clamp the pin 13 in fixed engagement with the diaphragm 11. The pin 13 is slidably mounted through the bearing plate 16 of the casing 10 and a spring 13a abuts the plate 16 at one end and the diaphragm 11 at its opposite end to draw the pin 13 inwardly when pressure is relieved from the diaphragm 11.

The abutment pin 13 is provided with a rounded forward end which abuts against the rear face of the angle lever 17, which lever 17 is pivotally connected to the casing 10, as at 18, and is adapted to operate a suitable type of valve control mechanism, one example of which is set forth in the following description. The lever 17 is provided with a protruding end 19 which extends horizontally when in an operative position and when the diaphragm 11 is in the position shown in full lines and when the diaphragm is subjected to pressure. This protruding end 19 projects through the slot 20 formed in the casing 10 and is rounded transversely as is clearly shown in

Figure 1. The casing 10 is provided with a vertical abutment wall 10a, against which abutment wall 10a the vertical portion of the lever 17 abuts for the full length of said vertical portion under pressure of the abutment pin 13 and diaphragm 11. This pressure will hold the lever 17 in a set clamped position against the wall 10a to support the link 21 until pressure is relieved from the diaphragm 11.

An actuating link 21 is provided with an eye or loop 22 at one end which loosely fits over the protruding end 19 of the lever 17 when in an operative position. The opposite end of the link 21 is pivotally connected to the valve 24. The valve 24 is carried by the supply line 25 for supplying gas, fuel oil, or the like, to a suitable burner or other apparatus through the pipe 26.

The operation of the device is as follows:

As the pressure within the casing 10 falls below a predetermined degree the diaphragm 11 will move from the full line position to the dotted line position, the spring 13a pushing the diaphragm to the extended position when pressure is relieved from the diaphragm. The actuating rod 15 will at that time pull the bell crank lever 17 from the full line to the dotted line position shown in Figure 1, and the eye 22 of the link 21 will slip from the protruding end 19. The weight of the link 21 will cause the arm 23 of the valve 24 to swing from the full line to the dotted line position, thereby completely cutting off the flow of fuel through the valve 24 from the pipe 25 to the pipe 26. This will provide a positive shut-off for the valve, and the connection between the operating mechanism and the valve will be definitely disconnected. The valve will not again be opened until the link 21 is manually attached to the protruding arm by an operator.

From the foregoing description it will be seen that a very simple and efficient means has been provided for definitely disconnecting the actuating mechanism from the valve-operating mechanism at a predetermined time or under predetermined conditions in a manner whereby the valve 24 will be completely and definitely closed.

It should be understood that certain detail changes in the construction of the device may be employed without departing from the spirit of the invention, so long as such changes fall within the scope of the appended claim.

Having described the invention, what is claimed is:

A bell crank actuating means comprising a casing, a vertical abutment wall carried by said casing, an angle lever pivotally secured at one

end to said casing adjacent the abutment wall and having a substantially vertical portion adapted to abut said abutment wall for the full length of the substantially vertical portion to limit the swing of said lever in one direction, said lever having a protruding end, a releasable link having an eye removably fitted over said protruding end, said protruding end normally extending in a substantially horizontal position beyond said abutment wall and said link being adapted to be releasably suspended by said protruding end, an abutment pin frictionally engaging said vertical portion of said lever for holding said vertical portion in a set clamped position against said abutment wall, and an actuating means for said pin for releasing the pin from engagement with the lever to facilitate the swinging of the horizontal portion of the lever downwardly and to thereby automatically release said releasable link from said lever and to cause said link to fall of its own weight from said protruding end of said lever by the pull of gravity.
